(57) **CLAIM**

The ornamental design for a chamber block, as shown and described.

DESCRIPTION

FIG. 1 is a front top perspective view of a chamber block which embodies the design;

FIG. 2 is a front bottom perspective view thereof;

FIG. 3 is a front view thereof;

FIG. 4 is a rear view thereof;

FIG. 5 is a right side view thereof; the left side view thereof being a mirror image of the right side view thereof;

FIG. 6 is a top view thereof; and,

FIG. 7 is a bottom view.

The structures depicted by means of broken lines in the figures have been shown for illustrative purposes only and form no part of the claimed design.
